UNITED STATES PATENT OFFICE.

THOMAS LE VORA, OF IOWA CITY, IOWA

CARPET-CLEANING DEVICE.

Application filed December 11, 1926. Serial No. 154,214.

This invention relates to new and useful improvements in cleaning devices that is primarily adapted for use in the cleaning of carpets and in particular for working soap 5 intimately into the nap of the carpet and to remove both the soap and grime with the least amount of labor.

A further and important object is to provide a cleaner of this character that is extremely simple of construction having a member for scraping engagement with the carpet surface so as to work the soap into the nap and being so constructed as to permit a charge of water to be continuously ejected onto the carpet during the cleaning operation.

Other objects will become apparent as the nature of the invention is better understood, the same comprising the novel form, combination, and arrangement of parts hereinafter more fully described, shown in the accompanying drawing and claimed.

In the drawing wherein like reference characters indicate corresponding parts throughout the several views:

Figure 1 is a view in side elevation, partly in section of a carpet cleaning device constructed in accordance with the present invention.

Figure 2 is a fragmentary back side elevation thereof also partly in section.

Now having particular reference to the drawing my novel carpet cleaner consists of a flat bar 5 preferably of wood, and of predetermined length that is formed centrally with a threaded hole for receiving an externally threaded and internally tapered flanged sleeve 6 within which is threaded the inner tapered end of an elongated pipe 7, that in reality forms the handle of the tool. Upon the opposite end of this pipe 7 is a valve 8 having an inlet nipple to which is attached a water hose 9 in communication with the house water supply.

Arranged upon the outer side of the bar 5 and at one edge thereof is a closed ended branch pipe 10 in communication with the discharge end of the pipe 7 as clearly disclosed in Figure 2. The bottom side of the branch pipe 10 is formed with water emitting openings 11, while arranged upon the outer side of the bar 5 adjacent the bottom thereof and in back of the branch pipe 10 is a scraping blade 12. When the device is disposed at the position indicated in Figure 1 and moved across the surface of a car-

pet by the hands of the operator, the blade 12 will serve to work up the nap of the carpet and force thereinto particles of soap that have been previously laid upon the carpet. 60 Obviously when the valve 8 is opened, the water will flow through the pipe 7 and thence through the openings in the branch pipe 10 to be projected upon the surface of the carpet so that the same will be worked 65 into the nap together with the soap with the result that the dirt dust, grime, and the like is brought to the surface, and thence scraped therefrom by reason of the blade 12.

It will thus be seen that I have provided 70 a highly novel, simple, and efficient carpet cleaner that is well adapted for the purposes heretofore designated, even though I have herein shown and described the invention as 75 consisting of certain detail structural elements, it is nevertheless to be understood that minor changes may be made therein without affecting the spirit and scope of the appended claims.

Having thus described the invention, what 80 I claim as new is:

1. In a carpet cleaning device, of the class described, a hollow handle adapted for communication at its upper end with a source of water supply, a cross bar secured on the 85 lower end of the hollow handle and through which a lower end of the handle extends, a water pipe arranged forwardly of the outer side of the cross bar and communicating with the lower end of the hollow handle, 90 said water pipe being provided with water emitting openings in the bottom thereof, and a scraping blade depending from the cross bar.

2. In a carpet cleaning device, a hollow 95 handle communicating at its upper end with a source of water supply, a cross bar provided with a central transverse opening, a sleeve secured in the opening, a lower end of the hollow handle extending through the 100 sleeve and secured therein, a water pipe disposed in parallel spaced relation with respect to the outer side of the cross bar the lower end of the hollow handle which projects beyond the outer side of the cross bar 105 extending into the water pipe, said water pipe being provided with water emitting openings in the bottom thereof, and a scraping blade depending from the cross bar.

3. In a carpet cleaning device, an elongated hollow handle having communication at its upper end with a source of water sup-

ply, a lower end of the handle being tapered and externally threaded, a cross bar formed with a tapered threaded transversely extending opening in the central portion thereof, 5 an externally threaded sleeve arranged in the threaded opening of the cross bar, said sleeve being internally threaded and tapered, the lower tapered end of the handle being threaded through the sleeve, a water pipe 10 closed at its respective ends and disposed longitudinally in parallel spaced relation

with respect to the outer side of the cross bar, the lower end of the handle extending into the water pipe, said water pipe being provided with a series of water emitting 15 openings in the bottom thereof, and a scraping blade secured at its upper edge portion to the outer side of the cross bar and depending therefrom.

In testimony whereof I affix my signature.

THOMAS LE VORA.
